UNITED STATES PATENT OFFICE

JACOB BROOKS, OF GRIMSBY, CANADA.

SUPPORT FOR FITTING DOORS.

No. 824,777.

Specification of Letters Patent.

Patented July 3, 1906.

Application filed March 1, 1906. Serial No. 303,588.

To all whom it may concern:

Be it known that I, JACOB BROOKS, a subject of the King of Great Britain, and a resident of Grimsby, in the county of Lincoln 5 and Province of Ontario, Canada, have invented new and useful Improvements in Supports for Fitting Doors, of which the following is a specification.

My invention consists of a device held in 10 position by its own pressure and supports or holds the door while it is being planed on its edges preparatory to fitting.

The objects of my invention are to provide 15 means for holding and steadyng a door in course of planing for fitting purposes; second, to provide a device for door-fitting purposes that can be speedily and simply placed in firm position; third, to provide a device for door-fitting purposes that can be adjusted 20 to fit within various widths of door-frames, and, fourth, to afford facilities for folding the device into compact form for varying purposes. I attain these objects by the mechanism illustrated in the accompanying drawings, in which—

Figure 1 is an elevation of the door-holder adjusted to position between the jambs or sides of the door-frame and with a door shown in position, said jambs and door shown broken, 25 also a piece broken out to show the nut of the screw. The upper broken lines show the holder previous to adjustment and the lower broken lines show the holder folded for carrying. Fig. 2 is a plan of the same. Fig. 3 is a detail elevation of the adjustable sliding 30 part of the device. Fig. 4 is a sectional end elevation through the broken vertical broken line A A of Fig. 2 of the drawings. Fig. 5 is a sectional end elevation through the 35 broken vertical line B B of Fig. 2 of the drawings.

Similar characters refer to similar parts throughout the several views.

In the drawings, C is a horizontal arm 40 and has a beveled end 2.

D is a horizontal extension-arm and is adapted to adjustment on the horizontal arm E.

The arm C has side flanges 3, the arm D 45 has side flanges 4, and the arm E has side flanges 5. All said flanges referred to add strength and stability to said arms. The inner end of the side flanges 5 of the arm E are hinged at 6 to the inner ends of the side 55 flanges 3 of the arm C. The upper part 7 of the arm C extends beyond the hinge 6 and

rests on the top of the arm E when both said arms are in horizontal position, as shown. The arm E has an oblong slot 8 in the upper part thereof and is shown in Figs. 3 and 4 of 60 the drawings. The arm D is adapted to slide on the arm E, and the arm D has lower interior lips 9, on which the flanges 5 of the arm E rests. A hand-screw F passes through the top of the arm D and through the slot 8 65 and into a nut 10 on the under side of the arm E to fasten the two arms D and E together. In Fig. 1 of the drawings the arms D and E have a piece broken out therefrom to show the nut 10 of the screw F. The slot 70 8 allows adjustment of the arms D and E—that is, the extension of the arm D—the drawings showing about the limit of the contraction of the arms D and E. The opposite or outer end parts of the arms D and C have 75 suitable sockets or recesses 12 for the insertion of rubber pads or cushions 13, which are secured in said sockets. The rubber pads must extend beyond the arms D and C, so as to prevent them engaging with the side jamb 80 J of the door-frame. The pads 13 are made of rubber or other flexible material, so that they might not deface the jambs when the arms D and C are pressed to position. On one side of the arms C are lugs 15, extending 85 therefrom, and between said lugs is inserted one end of a door H, with one side edge resting on the floor, in order that said door may be steadied and firmly held while the carpenter is hand-planing the opposite side 90 edge for fitting. When the door is in position, as shown, it is held very firmly and is capable of resisting any force that the carpenter may exert upon it in planing.

In order to place the device in position between the jambs of a door-frame, the arms are raised on the hinge 6, as shown in the upper broken line in Fig. 1 of the drawings, and the screw F tightened. Then the whole is pressed down to horizontal position and immovable between the door-jambs. The extension 7 of the arm C at this time engages with the top of the arm E and prevents said arms from dropping on the hinge 6. The lips 9 on the inner side of the flanges of the 105 arms D retain the arms D and E in horizontal and slidble position one with the other. The screw F, together with the slot 8, allows the arms to be extended to fit between various widths of door-frames. The top of the 110 arm E has a number of transverse lines 16, numbered to denote the setting of the arm D

to fit certain widths of door-frames. The lower broken lines in Fig. 1 show the arm C folded to the arm D for compactness when carrying the same.

5 What I claim as my invention, and desire to secure by Letters Patent, is—

1. In a support for fitting doors, arms hinged together, one of the arms to lock on the other arm when horizontal therewith, an 10 adjustable arm on one of the hinged arms, means for fastening the adjustable arm to parallel position therewith, and means on the side of the opposite hinged arm to hold the door.

15 2. In a support for fitting doors, arms hinged together, one of the arms extended to rest on the top of the other arm when both arms are horizontal, an adjustable arm on one of the hinged arms, means for fastening 20 the adjustable arm to parallel position therewith, means on the side of the opposite

hinged arm to hold the door, a socket on the outer end of the adjustable arm, a similar socket on the outer end of the opposite hinged arm and rubber pads secured in said 25 sockets.

3. In a support for fitting doors, horizontal arms hinged together and adapted to lock in horizontal position, a slideable arm on one of the hinged arms and extending beyond 30 thereof, means for adjusting the slideable arm, means for rigidly securing the slideable arm, means on the side of the opposite hinged arm for holding the door, a socket on the outer end of the door-holding arm, a similar socket 35 on the opposite and outer end of the slideable arm, and rubber pads secured in the sockets, and extending therefrom.

JACOB BROOKS.
